EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

NIPPER FOR TUFT WEAVING.

Application filed February 27, 1926. Serial No. 91,238.

This invention relates to yarn nippers for tuft weaving by which the individual tufts of yarn to be supplied to the fabric are transferred from a suitable yarn-carrier 5 after severance to position between the warp threads in the loom.

Such nippers comprise a pair of thin sheet metal jaws pivotally jointed together, face to face, so as to lie in the same plane. 10 As the entire thickness of a complete nipper is barely over one-sixteenth of an inch, and as there must be no lateral projection to catch against the warp threads between which the nippers must pass to insert the

15 yarn tufts, the provision of a pivotal joint construction that shall be stiff enough to preserve and maintain the alignment of the gripping jaws in the same plane and positively prevent their accidental separation has 20 presented a serious problem in this art.

Heretofore the contacting portions of the jaw members have been reduced to about one-half thickness, and a short rivet of a length corresponding to the thickness of the 25 nipper has been inserted in registering holes of the reduced portions and headed down into the counterbored outside faces of the assembled jaws to lie flush with the outside, but as each jaw at this point is only about

30 $\frac{3}{16}$ inch thick and the holding action of the necessarily very small counterbore is but slight, it is natural that the jaws should easily get out of alignment and frequently 35 pull apart, thus causing imperfect weaving of the fabric and injury to the loom.

In dealing with the problem I have devised a construction which dispenses with the customary pivotal rivet and which provides a fulcral pivotal joint formed by integral interlocking engaged portions of the two jaws. Another feature resides in the construction by which the reduced portion of one member is engaged by an overhanging portion projecting from the full thickness 40 of the other member so that it is reinforced against buckling or springing from its normal plane. By providing an interlocking engagement around the periphery instead of merely at the centre of the attaching member of one jaw a much broader holding engagement is afforded to resist lateral or twisting strains on either jaw; in fact by providing interlocking engagement

both near the centre and at the periphery of the attaching member a very rigid device, fully satisfying the most exacting requirements, is produced. 55

In the accompanying drawings I have illustrated a pair of nippers constructed according to the principles of this invention, 60 in which:

Figure 1 is a side elevation of a completely assembled nipper device embodying the invention.

Figure 2 is a cross section on the plane 65 2-2 of Figure 1 looking in the direction of the arrows.

Figure 3 is a detail view showing part of the main or supporting jaw before assembly in the complete device. 70

Figure 4 is a cross sectional view on the plane 4-4 of Figure 3 viewed in the direction of the arrows.

Figure 5 is a detail view showing a side elevation of the supported pivotal jaw before its assemblage into the complete structure. 75

Figure 6 is a cross sectional view on the plane 6-6 of Figure 5 looking in the direction of the arrows. 80

In the practice of my invention, according to the form illustrated in the drawings, the two pivotal jaws 1 and 2 may have the usual contour and are made of thin sheet or pressed metal. 85

The main or supporting jaw 1 of the couple is made with a counter-bored recess of segmental form extending half way through the jaw and whose peripheral circular wall 3 extends through an arc of substantially more than a half circle so that its ends, at the inner edge of the jaw 1, are distant substantially less than the diameter of the circle from each other. 90

The other jaw 2 is provided with a segmental attaching member 10, whose circular peripheral edge is dimensioned to fit inside the segmental recess of part 1, and is inwardly beveled as shown at 11. This attaching member 10 is also reduced to one-half the thickness of the body portion of the jaw 2, being cut away on its rear face so that when it is inserted in the segmental recess, against the bottom wall 6 thereof, its outer face will lie flush with the main 100 surface of the jaw 1, as shown in Figure 2. 105

The recessed or reduced portion of the jaw 1 is centrally bored, as shown at 4, for the purpose of forming the centering guide for the counter-boring tool, and around this central opening is left an annular ridge or boss 5, having the full thickness of the body portion of the jaw 1 so that the segmental recess is really of annular form. The underside of the reduced portion 6 is undercut or beveled as to that portion which projects beyond the two angularly disposed arms of the jaw 1. The reduced portion of the jaw 2 is circular throughout, thus leaving an arcuate wall as shown by the dotted lines 15 at 13 in Figure 5.

It will be understood that prior to the assembly of the two devices into operative relation the cutting away of the surfaces to form arcuate peripheral walls on the two jaws leaves those walls at right angles to the side faces of the respective jaws. Hence the attaching member 10 can be fitted smoothly inside the segmental pocket with its peripheral edge in contact with the arcuate wall 3 bounding the segmental recess, and with the central aperture 12 in the attaching member surrounding the annular boss 5 of the jaw 1.

In this assembled position the lateral faces 30 of the two jaws are flush with each other but there is nothing to prevent their separating.

Accordingly, by means of a suitable die embracing circular V-shaped ribs, the engaging walls of each member are crowded in 35 or upset to overhang the arcuate beveled edge portions of the other member, as clearly illustrated in Figure 2. This upsetting tool, to produce this dove-tailed or interlocking joint, is properly centered through the medium of the centering apertures 4.

It will be observed that the limited oscillation of the jaw 2 on its supporting jaw 1 is permitted by this arrangement, while at the same time, instead of having merely 45 the central portions of the two jaws connected by an attaching rivet as heretofore, the peripheral portion of the attaching member is interlocked with or overhung by the inwardly upset boundary wall 3 inside of 50 the circular upsetting grooves 3^a, while the beveled inside edge of the recess 12 of the jaw 2 is overhung by the overlapping or upset lip 5 of the central boss which is forced in when forming the circular upsetting groove 5^a in said boss.

Therefore, the attaching member is strongly held at its periphery as well as its interior point and in both places is engaged by an overhanging lip projecting from the full thickness of the jaw. With this arrangement 60 therefore, the possibility of the two jaws springing apart, under ordinary conditions of service, is practically eliminated and perfect alignment between the gripping teeth at 1^a and 2^a, in the yarn-nipping ends of the

jaws, is always maintained and preserved. Each reduced portion, therefore, affords complete reinforcement from the other and is engaged by an overhanging portion of the full thickness of the metal.

70

What I claim is:

1. A yarn-gripping device for tuft weaving, embracing in its construction a pair of flat sheet metal jaws pivotally jointed together to lie in the same plane by integrally formed interlocking portions forming circular dove-tailed engagement one with the other to prevent their separation.

75

2. A yarn-nipping device for tuft weaving, embracing in its construction a pair of pivotally connected gripping jaws of sheet metal comprising a supporting jaw formed on one face with a shallow recess of segmental form extending to one edge thereof, and a pivotal jaw having a segmental portion dimensioned to fit and turn inside said recess, the adjacent circularly curved engaging portions of the two jaws being partially lapped one over the other to prevent their separation while permitting limited 85 pivotal movement of the jaws in the same plane.

85

3. A nipper for tuft weaving, embracing in its construction two sheet metal jaws having respectively segmental male and female portions in dove-tailed engagement one with the other, thereby allowing the jaws to open and close in the same plane while preventing their separation.

95

4. A nipper for tuft weaving embracing in its construction two sheet metal jaws pivotally connected together to lie in the same plane and formed respectively with male and female segmental portions having circular dove-tailed engagement both interiorly and 100 peripherally, substantially as described.

100

5. A yarn nipper for tuft weaving embracing two thin sheet metal jaws pivotally connected to lie in the same plane, one jaw being formed with a segmental recess extending to its edge to form a counter-sunk bearing seat, the other being formed with a segmental attaching and bearing member having a beveled peripheral edge adapted to fit into said recess and to underlie adjacent 110 overhanging portions of the companion jaw.

110

6. A yarn nipper for tuft weaving embracing two pivotally connected yarn-gripping jaws each formed with circular bearing portions of reduced thickness to permit assemblage of the two jaws with their outside faces in flush relation, the reduced portions being operatively secured together by integral lip portions of one member overhanging 120 beveled edge portions of the other.

120

7. A yarn nipper for tuft weaving embracing two jaws pivotally secured together, one of which has a circular attaching member of reduced thickness seated in a counter-bored recess in the other, the attaching mem- 130

130

ber being overlapped interiorly and peripherally by overhanging portions of the recessed member.

8. A yarn nipper for tuft weaving embracing in combination two pivotally connected sheet metal gripping jaws lying in the same plane, one of which has a circular attaching member of reduced thickness ro-

tatably seated in a circular recess of the other, the two members being inseparably and rotatively connected by peripheral retaining lips extending approximately throughout an entire circle.

In witness whereof, I have subscribed the above specification.

EDGAR F. HATHAWAY.
